UNITED STATES PATENT OFFICE.

LIZZIE GISH, OF MODESTO, CALIFORNIA.

DOUCHE TABLE.

Application filed June 9, 1920. Serial No. 337,638.

To all whom it may concern:

Be it known that LIZZIE GISH, a citizen of the United States of America, residing at Modesto, in the county of Stanislaus and

State of California, has invented new and useful Improvements in Douche Tables, of which the following is a specification.

The object of the invention is to provide a simple, inexpensive and convenient surgical table adapted for domestic use as a means of facilitating the proper taking of douche treatments without requiring assistance, and with this object in view, the invention consists in a construction and combination of parts, of which a preferred embodiment is shown in the accompanying drawings, wherein:—

Figure 1, is a side view of the apparatus.

Figure 2, is a plan view of the same.

The device consists essentially of a table of which the top 10 is supported by a foldable end and intermediate legs 11 and 12 of a length such as to support the top at a convenient distance from the plane of the supporting surface as for example, 15 to 18 inches, to avoid the necessity of either climbing or stooping to any considerable extent when desiring to occupy the supported surface, said legs being provided with braces 13 which are slotted as shown at 14 to operate in connection with pins or studs 15, said slots having terminal offsets 16 in engagement with the pins or studs to lock the legs in their extended or operative positions.

The lengths of the supporting legs are screwed over the head end of the table toward the foot end thereof so as to dispose the table top at a slight downward inclination from the foot end toward the head end as a means of increasing the efficiency of the application of the treatment, a foldable standard 17 being pivotally mounted as at 18 upon the frame of the table near the foot end and being held in its upright or normal position by means of a folding brace 19 which is formed with a right angularly bent extremity 19' engageable in an eye formed in the standard 17'. Said support is preferably provided with a plu-

rality of openings 20 for selective engagement by a supporting hook 21 for maintaining a douche or fountain bag 22 at the desired elevation.

In the main or body portion of the table top near the foot end thereof, there is provided a rectangular opening 23 beneath which is supported a depressed tray 24 adapted for the reception of a bed pan or like receptacle which is thus maintained in a plane below the surface of the table and consequently in unobstructing relation therewith while adapted to properly perform its functions in preventing the flow of water or other douching liquid beyond the confines of the table and positioned at a short distance beyond the foot end of the table top are foot rests 25 supported by bracket arms 26 in convenient positions to enable the occupant of the table to maintain the proper posture while personally administering the douche.

It will be noted that when not in use the apparatus may be folded into a compact form with the supporting legs arranged in the plane of the top, so that it may readily be stored in a small space as under a bed or in a closet and when required the device can be readily set up to form a substantial support for the patient at a convenient distance from the floor to permit of administering a douche without requiring the attendance of an assistant. The device may be constructed substantially or entirely of metal and may be enamelled to facilitate maintaining the same in a sanitary condition and obviously the same may be constructed at a comparatively small cost owing to the fact that the essential elements thereof require little or no machine work in the construction thereof.

The invention having been described, what is claimed as new and useful is:—

A device for the purpose indicated having a frame and a top supported thereby, the frame being provided with foldable supporting legs of different lengths to dispose the top in an inclined position downwardly from the foot end toward the head, the top being formed with a rectangular opening 100

adjacent the foot end, a depressed tray carried by the top below the opening and closed on all sides so as to be accessible only through said opening, thereby adapting the tray for the reception of a receptacle to maintain the latter in a plane below the surface of the table and in un-

obstructing relation therewith, a foldable standard carried by the frame, and an adjustable douche bag support carried at the 10 upper extremity of the standard.

In testimony whereof she affixes her signature.

LIZZIE GISH.
